ADHESIVE EARRING CONSTRUCTION

Ilene M. Crigler, Alexandria, Va.; John F. Crigler, administrator c.t.a. of said Ilene M. Crigler, deceased

Application February 11, 1953, Serial No. 336,370

4 Claims. (Cl. 63—14)

This invention relates to improvements in earring construction, and more particularly to an improved and effective means for attaching the ornament portion of an earring to the ear of the wearer thereof.

Speaking generally, all earring constructions of which I am aware incorporate rigid ear-attaching means such as clips, screws and the like which are mechanically connected to the ornament portion so as to form a fixed part thereof. Aside from the fact that unless applied with uncomfortable pressure such prior rigid ear-attaching means are notoriously lacking in security with which they attach to the ear, and that their construction is usually complicated to a degree as to add substantially to the cost of manufacturing earrings, they are also open to the further objections that when attached to the ear they are unsightly if viewed from the rear of the head and they are moreover not sufficiently flexible as to conform to all sizes and shapes of the ear and ear parts to which they attach, with the result that an earring attaching means which is suitable to the ear of one person either does not fit or is uncomfortable when applied to the ear of another person.

With the above in mind, a principal object of the present invention is the provision of attaching means for earrings characterized by a practically unlimited security of attachment, inexpensive manufacture, non-rigid and in fact flexible construction enabling earrings to be worn with comfort, and an ability to conform to all shapes and contours of ears or ear parts.

A more particular object of the invention is the provision of earring attaching means capable of attaching to the ear by adhesion.

A further object of the invention is the provision of earring attaching means which may be applied simply by pressing the same with light finger pressure against the surface of the ear part to which it is desired to attach the earring.

A still further object of the invention is the provision of earring attaching means which when applied to the ear is substantially if not wholly concealed either by the structural parts of the ear or by the ornament portion of the earring.

Another object of the invention is the provision of earring attaching means characterized by ready attachability to any one of numerous ear parts, such as the floor of the concha, tragus, antitragus, and lobe, or to two of said ear parts jointly, such as the tragus and antitragus.

A further object of the invention is the provision of earring attaching means of a disposable nature; that is to say, ear attaching means which can be discarded after a single use.

Still another object of the invention is the provision of earring attaching means of a character which may be sold at low cost in quantity for one-time use, and to which any desired ornament portion suiting the taste or costume of the wearer may be simply coupled.

Still another object of the invention is the provision

2

of earring attaching means of a type which may be sold independently of the ornament portion of the earring, and to which any one of a plurality of ornament portions may be connected as desired for a particular occasion of wear.

The above and other objects and advantages of earring attaching means according to the invention will appear from the following detailed description thereof, taken with the accompanying drawings illustrating without limitation various forms which earring attaching means as herein contemplated may take, in which—

Fig. 1 illustrates the manner of application and use of one form of earring attaching means of the present invention and which is of the class adapted to attach to a posterior surface of the external ear such as the "floor" of the concha;

Fig. 2 is a section taken along line 2—2 of Fig. 1;

Fig. 3 is a plan view, with Fig. 4 being a section taken on line 4—4 thereof, generally illustrating the constructional details and the manner in which such attaching means is sold to and prepared for application by the user;

Figs. 5 and 6 are views similar to Figs. 3 and 4 illustrating a variant form of coupling tab by which the earring ornament portion may be coupled to the ear;

Figs. 7 and 8 are views corresponding generally to Figs. 1 and 2, which illustrate the manner of application and use of another form of earring attaching means;

Fig. 9 is a separated view illustrating in greater detail the attaching means illustrated in Figs. 7 and 8;

Figs. 10, 11 and Figs. 12, 13 are plan and section views illustrating variant forms of earring attaching means according to the invention and which are of a class primarily adapted to attach to a frontal surface or surfaces of the ear, although the Figs. 10 and 11 form may be

35 applied as well to frontal and inner ear surfaces jointly;

Fig. 14 is a view similar to Figs. 1 and 7 specifically illustrating various ways of applying the Figs. 10 and 11 form of attaching means, but which is also representative of possible applications of the Figs. 12 and 13 form;

40 Figs. 15, 16 and 17 illustrate the constructional details and the manner of application and use of yet another form of earring attaching means according to the invention and which attaches to a frontal surface or jointly to frontal and posterior or inner surfaces of the ear; and

45 Figs. 18, 19 and 20 are views corresponding to Figs. 15, 16 and 17, respectively, illustrating the attaching means according to said views adapted to be secured to the inner surfaces such as the posterior surfaces of the tragus and antitragus of the ear.

50 The present invention stems from my appreciation that the anatomy of the human ear is such as to provide numerous surfaces to which earring attaching means made at least in part from adhesive tape material or equivalent may be attached with the same high security with

55 which adhesive tape as employed in surgical dressings, so-called "Band-Aids," etc., secures to other surfaces of the human body. In furtherance thereof, I have devised numerous forms of earring attaching means operating on the adhesive tape principle and being thereby adapted

60 to be secured by adhesion to an ear surface or a plurality of such surfaces, and which at the same time incorporate a coupling portion to which a separate earring ornament portion having any one of a variety of shapes, designs and forms (including natural and artificial flowers) may be simply coupled in position to achieve at least the ornamental effect provided by conventional earrings.

65 Referring to Figs. 1—4, illustrating one form of earring attaching means according to this invention, and the manner of application and use thereof, such is of the type whose body or attaching portion is designed to attach to the generally horizontal surface or "floor"

of the concha of the ear, in position such that its coupling portion extends forwardly and outwardly through the intertragic notch, i.e. the U-shaped opening separating the tragus and anti-tragus of the external ear, and to which a separate earring ornament portion may be hooked or otherwise secured to said attaching portion and hence to the ear.

To this end, the body portion designated 10 is fashioned from adhesive tape material as the term is defined broadly hereinafter, and illustratively comprises an elongated piece or strip of such material having rounded end edges, the rounded ends providing what may be termed wings 10a, 10b. Being constructed from adhesive tape material, as above, the under surface of the body portion 10 carries throughout its full area an adhesive substance 12 (Fig. 3), for which the material of the body portion provides a backing, and which may be any of the adhesive substances employed in adhesive tape manufacture. The coupling portion designated 14 of said attaching means illustratively comprises a tab-like formation fashioned integrally with said body portion but whose corresponding under surface is preferably devoid of adhesive. As seen in Fig. 3, the coupling portion 14 depends from the body portion 10 in the manner of the vertical leg of a T, whereby the body and coupling portions together have general T-shape, and its lower end is provided with a small opening 16 shown to be circular but which may have other shapes or may comprise a simple slit. As sold to the user, the adhesive surface 12 is protected by a covering 18, usually made of an open-mesh fabric, which is adapted to be stripped off the body portion immediately prior to applying the attaching means to the ear.

The dimensions of the aforesaid body and coupling portions 10, 14 are not unduly critical except that the body portion shall have length and width corresponding generally to the floor of the concha, whereby it may seat on same without puckering and also without the end wing 10b extending into the meatus or external opening of the external auditory canal. The width of the coupling portion 14 should not be substantially greater than the average width of the intertragic notch although in this connection it should be noted that, since both the body and coupling portions are made from flexible material, some oversizing is not objectionable as said parts may fold or otherwise conform themselves to the ear surfaces or parts on which they seat or through which they extend. The length of the tab-like coupling portion 14 is such that its free end extends forwardly of the frontal surfaces of the tragus and anti-tragus a sufficient distance that it may be grasped by the fingers and tautened, thus to expose and ready the hole 16 for the reception of the ornament portion or coupling element thereof.

The term "adhesive tape material" as employed in the foregoing to designate the material from which at least the attaching portion 10 is fashioned is intended to embrace the various types of adhesive tape materials wherein the backing for the adhesive is made from fabric or fibrous material, and also the various adhesive tape materials whose backing is made from plastic and whose securing face is either coated with adhesive or is inherently tacky. In case of the backing being made of fabric or fibrous material, it is preferred that the fabric be of expansible or elasticized construction and, when it is fashioned from plastic, that such have a degree of stretch corresponding to that characterizing elasticized fabric. The ability of the backing material to stretch is particularly of advantage in connection with the tab portion 14, as it enables the tab to stretch when tautened as above, which in turn facilitates the coupling of the ornamental portion thereto.

The manner of applying and using earring attaching means of the invention will be apparent from a consideration of Figs. 1 and 2. It will be understood that prior to applying the attaching means as aforesaid to the ear, the mesh covering 18 is stripped from the adhesive sur-

face 12. Thereupon the attaching means may be held with its adhesive surface 12 facing downwardly, by grasping the coupling tab 14 between the thumb and forefinger, and inserted into the concha C of the ear, in position such that the tab portion 14 is aligned with the upper open end of the intertragic notch N. In a final operation, the body attaching portion 10 is pressed downwardly and smoothed against the "floor" of the concha by pressure of the fore-finger, whereupon it secures itself by adhesion to the floor surface in the manner best illustrated in Fig. 2. Due to the positioning of the tab portion 14 in alignment with the intertragic notch N, such downward movement results in said tab portion projecting forwardly through the lower end of said notch, thus to expose the opening 16. Any desired ornament portion generally designated 20 and which is illustratively provided with a coupling hook 21 may now be coupled to the tab 14, by the simple operation of passing the hook 21 through the eye or opening 16. In the event the ornament portion consists of a natural or artificial flower, the stem thereof may be threaded through the tab opening 16, thus to dispose the bloom in covering relation to the concha opening and adjacent ear parts.

Earring attaching means as described has numerous advantages, among which may be noted inexpensive manufacture, ease of attachment, and a high degree of security approaching, if not equalling, the security with which conventional adhesive tape secures itself to the human body. Equally important is the fact that since earring attaching means according to the invention is inherently soft and flexible, such may be worn with comfort by all persons regardless of individual ear shaping and contour. Another feature of advantage is that when secured to the floor of the concha as illustrated, the attaching means is substantially concealed both by the ear parts disposed forwardly thereof and by the ornament portion 20. Such concealment may of course be heightened by fashioning the attaching means from flesh-colored adhesive tape material. Yet another advantage is that in use the tab portion 14 is free to rest directly on the lower-end edge of the intertragic notch N and transmits thereto an appreciable fraction of the weight of the ornament portion 20, which is a desirable feature in the case of said ornament portion having substantial weight. When it is desired to remove the earring, it is only necessary to uncouple the ornament portion 20 from the attaching means and thereupon strip same from the ear, whereupon it may be discarded or otherwise disposed of. Instead of being stripped from the ear and disposed of immediately following each wearing period, the attaching means may of course be retained in the ear for a repeat use thereof, or for interchange of ornament portion.

Referring to the form of earring attaching means illustrated in Figs. 5 and 6, such corresponds to the previously described form in all essential respects, differing therefrom only in that the coupling tab 14', rather than being formed integral with the body or attaching portion 10', is formed separately therefrom and secured to the outer face of the body portion as by cementing. Said coupling tab 14' according to the variant form may be fashioned from stretchable material such as rubber. The rubber coupling tab 14' is of advantage when it is desired to use an ornament portion of a type to be worn close to the ear frontal surfaces. Thus, by a proper choice of the length of the coupling tab 14', which requires that it is pulled outwardly and stretched somewhat to effect coupling the ornament portion thereto, the rubber tab functions to draw the ornament portion snugly against the frontal surfaces of the tragus T and antitragus AT, thus adding to the security with which said ornament portion is attached to the ear.

According to the invention, it is also possible to construct the coupling portion of the attaching means from means other than fabric or rubber. For example, referring to Figs. 7, 8 and 9, the coupling portion is pro-

vided by a length of fine wire twisted on itself intermediate its ends so as to form a twisted length portion 22 terminating in a coupling eye 24 extending laterally from one longitudinal edge of the body portion 26, to which latter the wire ends 28a, 28b are secured. Such securing may be simply effected by fashioning the body portion 26 from two plies 26a, 26b (Fig. 8) of adhesive tape material, of which the upper ply 26a adhesively secures itself to the under plies 26b. By inserting the wire ends 28a, 28b between said plies prior to their securing as aforesaid, said ends are effectively secured upon the plies being adhesively associated. If the wire is made from metal, it may be sheathed with a fabric covering or with a soft plastic, thus to obviate any discomfort occasioned by contact of metal wire with the skin. Or the wire may be fashioned wholly from plastic material extruded to wire form, as conventional in making plastic ties.

By reference to Figs. 7 and 8, it will be seen that the body or attaching portion 26 as shown in Fig. 9 may be adhesively secured to the floor of the concha, as with the prior forms, with the twisted length portion 22 of the wire coupling means extending through the intertragic notch so as to dispose the coupling eye 24 forwardly or outwardly of the adjacent frontal surfaces of the tragus and antitragus. Due to the flexibility of the wire making up said coupling means, the eye 24 may be bent or tightened by finger pressure to obtain the best holding characteristics. The twisted length portion 22 may also be bent to seat on the curved end edge of the intertragic notch, thus to secure the advantage of such a disposition as stated above.

For certain types of ornament portions, particularly where the latter have the form of a natural or artificial flower, it is desirable to incorporate a plane backing therefor, so that the flower-type ornament portion will not have any substantial direct contact with the ear surfaces. Such a backing may be provided as by a disc 30 of transparent material provided with a central aperture 32 enabling same to be slipped over the coupling eye 24 and positioned in the manner illustrated in Figs. 7 and 8, thus to provide a backing for the flower-type ornament portion whose stem is adapted to lock the backing disc 30 in place.

Whereas the prior described forms of earring attaching means are of the type which adhesively secure to the inner or posterior ear surfaces as represented by the "floor" of the concha, Figs. 10-14 illustrates such attaching means designed primarily for securing to the outer ear surfaces, such as the frontal surfaces of the tragus and antitragus and of the ear lobe. Referring first to the Figs. 10 and 11 form, such comprises a body or attaching portion 34 made from adhesive tape material as defined in the foregoing, and which is provided with coupling means shown to be in the nature of an eye or loop 36 (preferably non-adhesive on its under face) struck out from the material of said body portion as by cutting through the same with short-length slits 36a, 36b, but which may be provided in other ways, such as by cementing the ends of a short strip of rubber to the outer face of said body portion. As seen in Fig. 14, the body portion may be applied jointly against the frontal surfaces of the tragus and antitragus and in bridging relation to the intertragic notch. Or, as indicated in dotted lines, the body portion may be adhesively attached to the frontal surface of the ear lobe. Additionally, attaching means as illustrated in Figs. 10 and 11 may be applied by bending the same to U-form and pressing or pinching it over the more or less vertical edge of the tragus T, so that one arm or leg of the U secures to the frontal surface, the other arm secures to the inner surface thereof, and the eye 36 projects rearwardly into the concha opening. The last described disposition of the attaching means is illustrated in the upper dotted line showing in Fig. 14. Regardless of the par-

ticular surface or surfaces to which applied, the ornament portion may be coupled to the attaching means by passing its hook or other coupling element including a flower stem through the coupling eye 36.

5 The same mode of application is possible with the further form of earring attaching means illustrated in Figs. 12 and 13. This latter form incorporates a hook type, rather than the eye form of coupling portion as previously described. Such hook type coupling means may be provided by bending a length of wire so that it provides an upwardly directed hook 38 intermediate its ends 38a, 38b, which latter are secured to the body or attaching portion 40 as by disposing said ends between the adhesive tape plies 40a, 40b, from which said body portion is fashioned.

10 Earring attaching means as illustrated in Figs. 12 and 13 may be applied as illustrated in Fig. 14, but it will be understood that the ornament portion to be coupled thereto will be provided with an eye or equivalent, rather than with the hook-type coupling element 21 as illustrated in Figs. 1 and 2.

15 The advantages of an earring attaching means as previously described, together with some additional advantages to be explained, are achieved by the still further form of attaching means as illustrated in Figs. 15-17. In this latter form, the body portion of the attaching means, rather than being made from a single piece of adhesive material, may be fashioned from two sections 44, 46 of such material coupled together in laterally spaced relation by coupling means which also provide the coupling portion to which the ornament portion of the earring attaches or threads through. As illustrated, said coupling means preferably takes the form of two spaced lengths of spring wire 48, 49 whose ends 48a, 48b and 49a, 49b are secured to the sections 44, 46, respectively. Said wires are coiled intermediate their ends to the form of eyes 50, 52 contained in the space between the sections and being slightly offset from the plane of said sections in the direction of the outer or non-adhesive surfaces thereof. Securement of the wire ends 48a, 48b and 49a, 49b to the sections of the body or attaching portion may be simply effected as by fashioning the sections from plies 44a, 44b and 46a, 46b of adhesive tape material and sandwiching said wire ends therebetween prior to the plies being adhesively secured to one another. Instead of forming the eyes 50, 52 from two lengths of wire as aforesaid, they may be formed from a single length of wire, or from a continuous wire loop, bent or fashioned so as to provide two spaced wires extending between the sections 44, 46. A single protective covering 54 dimensioned so as to cover the adhesive surfaces of both sections may be included to protect such surfaces prior to applying the attaching means to the ear.

20 25 30 35 40 45 50 55 60 65 70 The sectional type attaching means with the ornament coupling portion thereof disposed between the body forming sections thereof may be applied in numerous ways. Referring to Fig. 17, such may be applied to the external surface of the ear lobe, or it may be applied to the frontal surfaces of the tragus and antitragus and in bridging relation to the intertragic notch, as in Fig. 14. It may also be applied by folding the sections so that they extend in parallel relation and with their adhesive surfaces facing one another, and thereupon pressing or pinching them together over the edge of the tragus or over the under edge of the ear lobe, with the result that one section secures to the frontal or anterior surface of the ear part and the companion section attaches to the generally parallel posterior or inner surface of said ear part. When pinched over the ear parts as aforesaid, the coupling eyes 50, 52 project beyond said edge in position such that the earring ornament portion may be simply and effectively coupled therewith. If the position of the spaced eyes 50, 52 is not the most advantageous, said eyes may be simply bent as required for

best holding results. The aforesaid eye arrangement is ideally suited to the securement of the stems of natural or artificial flowers used as the ornament portion, not only because the spacing of the eyes gives stabilizing effect, but also because the eyes may be simply adjusted by squeezing to the size of a particular flower stem being secured.

It is also possible to adapt the sectional type earring attaching means illustrated in Figs. 15-17 so that the same may be secured to posterior or inner surfaces of the ear. Referring to Figs. 18, 19 and 20, the earring attaching means therein illustrated corresponds to such means as illustrated in Figs. 15 and 16, with the exception that the coupling eyes 56, 58 are disposed laterally forwardly of the adhesive faces of the sections 60, 62 making up the body or attaching portion thereof. Thus, when the sections 60, 62 are dimensioned so as to seat on the posterior surfaces of the tragus and antitragus, as illustrated in Fig. 20, the coupling eyes 56, 58 project forwardly through the intertragic notch and are thus in a good position to receive the stem of a flower-type or equivalent ornament portion.

Without further analysis, it will be seen that all of the illustrated forms of earring attaching means according to the present invention achieve the desirable objectives therefor outlined in the foregoing. Being fashioned either wholly or in great part from adhesive tape material, earring attaching means as herein contemplated may not only be inexpensively manufactured, but also they possess a high security of attachment, they are so flexible and shape-conforming that they may be worn without any discomfort, and they are universal to all types and shapes of the individual ear. Another advantage of the present earring attaching means is that they are substantially entirely concealed (Figs. 1-9 and Figs. 18-20 forms) and when not concealed are so unobtrusively positioned (Figs. 10-17 forms) that they are not at all unsightly when properly applied. That is to say, attaching means according to the latter forms are effectively if not wholly masked by the ornament portion. It is also a feature of the invention that the body portions of the attaching means of the Figs. 10-17 forms may be contoured and colored so as to blend into or match the ornament portion. For example, if the ornament portion employed is a flower, said body portions may be colored green and shaped as a leaf or a pair of leaves of the particular flower. In this way, the attaching means, to the small extent that it may be viewable from directly in front of the ear, is rendered not only unobtrusive but also ornamental.

As many changes could be made in carrying out the above constructions without departing from the scope of the invention, it is intended that all matter contained in the above description or shown in the accompanying drawings shall be interpreted as illustrative and not in a limiting sense.

I claim:

1. Single-use disposable earring attaching means comprising an elongated body portion of flexible material having an adhesive under surface so as to be attachable by adhesion to an ear surface and detachable from said surface by stripping therefrom, coupling means for coupling a selected earring-ornament portion to said body portion comprising means separate from said body portion and being devoid of adhesive and being affixed to

and extending from approximately the middle of said body portion and forming connector-eye means for detachably receiving complementary connector-pin means carried by said earring-ornament portion, said ornament-coupling means being constructed and arranged as to enable the earring-ornament portion to be connected to said body portion following attachment of the latter to said ear surface as aforesaid, said body portion being shaped and dimensioned so as to extend substantially coextensive with and thereby to seat on the "floor" of the concha of the ear, and said coupling means projecting from the body portion and having width and length as to extend through and terminate a slight distance forwardly of the intertragic notch opening to said concha.

2. Single-use disposable earring attaching means comprising an elongated body portion of flexible material having an adhesive under surface so as to be attachable by adhesion to an ear surface and detachable from said surface by stripping therefrom, coupling means for coupling a selected earring-ornament portion to said body portion comprising means separate from said body portion and being devoid of adhesive and being affixed to and extending from approximately the middle of said body portion and forming connector-eye means for detachably receiving complementary connector-pin means carried by said earring-ornament portion, said ornament-coupling means being constructed and arranged as to enable the earring-ornament portion to be connected to said body portion following attachment of the latter to said ear surface as aforesaid, said body portion being shaped and dimensioned so as to extend substantially coextensive with and thereby to seat on the "floor" of the concha of the ear, and said coupling means comprises a non-adhesively surfaced tab-like formation extending laterally from said body portion and being dimensioned to project forwardly through the intertragic notch opening into the concha, said coupling portion being provided at its projecting end with an opening through which a part of said ornament portion may be passed.

3. Single-use disposable earring attaching means substantially as set forth in claim 2, wherein said tab-like formation comprises a strip of stretchable material affixed to said body portion.

4. Single-use disposable earring attaching means substantially as set forth in claim 1, wherein said coupling means extends from a longitudinal edge of said body portion and comprises an eye fashioned from a length of spring wire twisted intermediate its ends to form a closed loop and whose ends extend and are affixed to said body portion.
